UNITED STATES PATENT OFFICE

WILLIAM D. COLLINS, OF EVANSVILLE, INDIANA, ASSIGNOR TO SERVEL INC., OF NEW YORK, N. Y., A CORPORATION OF DELAWARE

DESIGN FOR A REFRIGERATOR CABINET

Application filed August 2, 1930. Serial No. 36,535. Term of patent 3½ years.

To all whom it may concern:

Be it known that I, WILLIAM D. COLLINS, a citizen of the United States, residing at Evansville, in the county of Vanderburg and State of Indiana, have invented a new, original, and ornamental Design for Refrigerator Cabinet, of which the following is a specification, reference being had to the accompanying drawing, forming part thereof.

Fig. 1 is a front view of a refrigerator cabinet, showing my new design, and Fig. 2 is a side elevation.

I claim:

The ornamental design for a refrigerator cabinet, as shown.

WILLIAM D. COLLINS.
